Primary Examiner—Alan P. Douglas*Assistant Examiner*—Caron D. Veynar*Attorney, Agent, or Firm*—Richard C. Litman**[57] CLAIM**

The ornamental design for an elongated cooking utensil, as shown and described.

DESCRIPTION

FIG. 1 is a perspective view of an elongated cooking utensil showing my new design;

FIG. 2 is a top plan view thereof;

FIG. 3 is a rear elevational view;

FIG. 4 is a front elevational view thereof;

FIG. 5 is a right side elevational view with the left side being a mirror image thereof; and,

FIG. 6 is a bottom view thereof.

The broken line showing of the fish is for illustrative purposes only and forms no part of the claimed design.

FIG. 1

FIG. 2

FIG. 3

FIG. 4

FIG. 5

FIG. 6
